(57) **CLAIM**

The ornamental design for a mesh basket, as shown and described.

DESCRIPTION

FIG. 1 is a perspective view of a mesh basket showing our new design;

FIG. 2 is a front view thereof, the rear view being identical thereto;

FIG. 3 is a left side view thereof, the right side view being identical thereto;

FIG. 4 is a top view thereof; and,

FIG. 5 is a bottom view thereof.

The broken lines illustrate portions of the mesh basket and form no part of the claimed design.
